(57) **CLAIM**

I claim the ornamental design for a wearable device, as shown and described.

DESCRIPTION

FIG. 1 is a frontal view of a wearable device in accordance with the present design as worn by an operator, wherein the broken line showing a face of the operator is for illustrative purposes only and forms no part of the claimed design; FIG. 2 is a perspective view thereof; FIG. 3 is a front view thereof; FIG. 4 is a rear view thereof; FIG. 5 is a right side view thereof; FIG. 6 is a right side view thereof; FIG. 7 is a top plan view thereof; and, FIG. 8 is a bottom plan view thereof.
